UNITED STATES PATENT OFFICE

163,778

AIRPLANE

Chester V. Sol and Paul Graban, Hobart, Ind.

Application May 12, 1950, Serial No. 9,906

Term of patent 14 years

(Cl. D71—1)

To all whom it may concern:

Be it known that we, Chester V. Sol and Paul Graban, citizens of the United States, residing at Hobart, in the county of Lake and State of Indiana, have invented a new, original, and ornamental Design for an Airplane, of which the following is a specification, reference being had to the accompanying drawing, forming part thereof.

Figure 1 is a rear perspective view of an airplane, showing our new design;

Figure 2 is a side elevational view with the landing gear shown in an extended position;

Figure 3 is a top plan view;

Figure 4 is a front elevational view; and

Figure 5 is a rear elevational view.

The characteristic features of our design reside in the parts shown by means of full lines in the drawings.

We claim:

The ornamental design for an airplane, as shown and described.

CHESTER V. SOL.
PAUL GRABAN.
